UNITED STATES PATENT OFFICE

MILTON E. CHRISTIANSON, OF JASPER, MINNESOTA

ARCH SUPPORT

Application filed June 14, 1928. Serial No. 285,437.

The present invention is directed to improvements in arch supports, and is an improvement of my co-pending application filed April 16, 1928, Serial Number 270,345.

5 The primary object of the invention is to provide a device of this character so constructed that the arch supporting web is so arranged that both stretches thereof will aid in supporting the arch of the user.

10 Another object of the invention is to provide an arch supporter so constructed that the elastic web thereof can be adjusted as the same loses its elasticity.

15 Another object of the invention is to provide a device of this character including a frame so constructed that it can be permanently attached to the shoe should it be desired.

20 With these and other objects in view, this invention resides in the novel features of construction, formation, combination and arrangement of parts to be hereinafter more fully described, claimed and illustrated in the accompanying drawing, in which:—

25 Figure 1 is a top plan view, with parts broken away.

Figure 2 is a bottom plan view.

Figure 3 is a longitudinal sectional view.

Referring to the drawing 1 designates a 30 frame formed of suitable sheet metal and includes side bars 2 and end bars 3, said end bars being curved longitudinally in order to impart to the frame a general curvature. An elastic web 4 is employed and is of such width 35 as to occupy the space between the end bars 3, said web having its terminals secured by a lace 5, said terminals being so arranged as to occur in the bottom stretch of the web.

Upon reference to Figure 2 it will be noted 40 that the web is provided with a plurality of perforations 6, said perforations being so arranged that after the web loses some of its elasticity and if it is desired to adjust the same the web can be cut on the line A—B and the lace then engaged in the openings 6.

If desired the lace may be eliminated, and the ends of the webs permanently connected.

In order to prevent wear upon the web the side bars 2 may be covered with a webbing 7, 50 thus preventing the web from coming in di-

rect contact with the metallic bars and consequently preventing wear thereto.

The end bars 3 are provided with openings 8 and through which securing devices may be passed for securing the device within the 55 shoe, and it will be further observed that the structure is such that if desired the insole can be placed over the bars 3 during the manufacture of the shoe in order that the arch support will form a permanent part thereof.

By stretching the web as shown, it will be 60 obvious that pressure upon the upper stretch thereof will be sufficient to cause this stretch to sag and engage the lower stretch and in this manner both stretches will be subjected 65 to strain.

The drawing illustrates the support for use in connection with the right shoe. It will be noted that the bar 2 which engages, in this instance, the right side of the shoe is inclined 70 upwardly and curved longitudinally in order that it will properly fit the shoe and hold the web effectively stretched. The right hand end bar is slightly tapered to more readily conform to the shape of the shoe. It will be 75 of course understood that the same can be reversed for use in connection with the left shoe.

It will be further observed that the curvature of the end bars 3 is such that the highest point of the support will be located against the inner side of the shoe, thus effectively supporting the arch.

Recesses 9 are formed at points where the end and side bars merge, and in which engage the free edges of the web 5. It will thus be seen that the web will be held against slipping longitudinally of the frame, and owing to the fact that the end bars are bowed inwardly the upper stretch of the web will 90 overhang the end bars 3.

From the foregoing, it is thought that the construction, operation and many advantages of the herein described invention will be apparent to those skilled in the art, without further description, and it will be understood 95 that various changes in the size, shape, and proportion and minor details of construction may be resorted to without departing from 100

the spirit or sacrificing any of the advantages of the invention.

What is claimed is:—

1. An arch support comprising a frame including side bars disposed in different planes, a web supported by said bars, the stretches thereof being disposed one above the other and in inclined planes.
- 10 2. An arch support comprising a frame including side and end bars, said end bars being curved longitudinally to maintain one side bar above the plane of the other, and a web supported by the side bars and held against longitudinal movement by the end bars.
- 15 3. An arch support comprising a frame including side and end bars, one of the side bars being transversely inclined and curved longitudinally, and a web supported by the side bars and held against longitudinal movement by the end bars.

In testimony whereof I affix my signature.

MILTON E. CHRISTIANSON. [L. S.]
